(57) **CLAIM**

The ornamental design for a portable pizza oven, as shown and described.

DESCRIPTION

FIG. 1 is a top perspective view of a portable pizza oven showing our new design;

FIG. 2 is a top plan view thereof;

FIG. 3 is a rear elevational view thereof;

FIG. 4 is a left side elevational view thereof, the right side being a mirror image;

FIG. 5 is a front elevational view thereof, and

FIG. 6 is a right side elevational view thereof with the cover of the portable pizza oven lifted off of the base.

FIG. 7 is a top perspective view of a second embodiment thereof;

FIG. 8 is a top plan view of FIG. 7;

FIG. 9 is a rear elevational view of FIG. 7;

FIG. 10 is a left side elevational view of FIG. 7, the right side being a mirror image;

FIG. 11 is a front elevational view of FIG. 7; and,

FIG. 12 is a right side elevational view of FIG. 7 with the cover lifted off the base.

The broken lines in FIGS. 1-12 represent cover vent holes, a temperature reading gauge, a temperature adjustment dial and support legs that form no part of the claimed design.
